UNITED STATES PATENT OFFICE

156,019

DESIGN FOR A BOTTLE CAP OR SIMILAR
ARTICLE

John J. Lynch, Brooklyn, N. Y.

Application December 4, 1945, Serial No. 124,343

Term of patent 14 years

(Cl. D58—26)

To all whom it may concern:

Be it known that I, John J. Lynch, a citizen of the United States, residing at Brooklyn, county of Kings, and State of New York, have invented a new, original, and ornamental Design for a Bottle Cap or Similar Article, of which the following is a specification, reference being had to the accompanying drawing, forming a part thereof.

Figure 1 is a perspective view of a bottle cap or similar article, showing my new design;

Figure 2 is a reversed front view thereof on a reduced scale;

Figure 3 is a partial cross-section thereof taken substantially on the line 3—3 of Figure 2;

Figure 4 is a top plan view thereof on a reduced scale, and

Figure 5 is a side elevational view thereof.

The simulation of a finger nail on my design may be the same color as the contents of the container on which the design is used.

I claim:

The ornamental design for a bottle cap or similar article, as shown and described.

JOHN J. LYNCH,
